FENDER FLAP

Morley Markson, Toronto, Ontario, Canada, assignor to National Rubber Company Limited, Toronto, Ontario,
Canada, a corporation of Canada

Filed Oct. 12, 1964, Ser. No. 82,127

Term of patent 14 years

(Cl. D14—6)

FIG. 1

FIG. 3

FIG. 1 is a front perspective view of a fender flap, showing my new design;

FIG. 2 is a rear perspective view thereof and

FIG. 3 is a side elevational view thereof.

The right side of the fender flap which is not shown in the drawing corresponds to the left side which is illustrated.

I claim:

The ornamental design for a fender flap, substantially as shown and described.
